UNITED STATES PATENT OFFICE.

SAMUEL BERGSTEIN, OF MIDDLETOWN, OHIO, ASSIGNOR TO THE INTERSTATE FOLDING BOX COMPANY, OF MIDDLETOWN, OHIO.

PAPER-BOX-MAKING MACHINE AND THE LIKE.

Application filed October 11, 1923. Serial No. 667,919.

To all whom it may concern:

Be it known that I, SAMUEL BERGSTEIN, a citizen of the United States, residing at Middletown, in the county of Butler and 5 State of Ohio, have invented certain new and useful Improvements in Paper-Box-Making Machines and the like, of which the following is a specification, reference being had therein to the accompanying drawings. 10 This invention relates to improvements in machines for making paper folding boxes, the principle of the invention being generally applicable to paper box making machines, and applying more particularly in 15 the form herein shown and described to machines of the character set forth in United States Patent No. 1,461,966, issued July 17, 1923.

Machines of this character are adapted 20 for large, low-cost production, the folding of the paper blanks, from which the boxes are made, gluing of the joints, and delivery of the boxes from the machine in knocked-down form being performed automatically. 25

As in the case of the machine of the patent above referred to, the present invention is adaptable to have suitable adjustments made thereof for making boxes of 30 various shapes and sizes, the arrangement of the machine, as herein shown and described for illustrative purposes, being for the production of a common type of hand-made box modified to adapt the same for 35 machine production.

The main objects attained in the invention consist in improved mechanisms for folding the boxes, for applying the glue thereto for the joints, and for forming the 40 joints, whereby uniformity of production and uninterrupted operation of the machine are obtained. The improvements in this respect consist of suitable mechanisms for using air pressure for operating certain of 45 the mechanism for folding the box blanks and also for operating the gluing mechanism.

These and other objects set forth in the detailed specification hereof are realized in 50 a machine as illustrated and described herein and defined and comprehended in the appended claims.

In the accompanying drawings:

Fig. 1, is a plan view of the machine; 55 Fig. 2, is a side elevation;

Fig. 3, is an enlarged plan view of a detail of the machine;

Fig. 4, is a longitudinal sectional view taken on line 4—4 of Fig. 3;

Fig. 5, is a cross sectional view taken on 60 line 5—5 of Fig. 4;

Fig. 6, is a detail view of the paper blank folding mechanism on line 6—6 of Fig. 3;

Fig. 7, is an enlarged view of a detail 65 of an air cylinder;

Fig. 8, is a plan view of Fig. 7;

Fig. 9, is a detail view of the valve controlling mechanism of the air line for operating the folding gluing mechanism;

Fig. 10, is a side elevation of Fig. 9; 70

Fig. 11, is a plan view of a box blank;

Fig. 12, is a plan view of the blank shown in Fig. 11, partially folded.

Fig. 13 is a detail view of devices which act to initiate the first fold on the box 75 blanks.

The improved machine in the general organization comprises as best shown in Fig. 1, a feeding mechanism —A, for the box blanks, folding mechanisms —B —C —E for 80 blanks, and a gluing mechanism —D, these mechanisms being arranged in coordinated relations one to another and with respect to the machine as a whole, whereby to adapt the machine for forming and gluing the 85 boxes with constant forward movement of the blanks which makes possible the large production capacity of the machine.

The machine as a whole is supported on a main frame comprising side frames —1, 90 supported on legs —2, and joined one to the other by up-standing cross frames —3.

The feeding mechanism, as here shown, is of a well known commercial type for feeding paper sheets. No novelty is claimed 95 relative to this part of the machine, as any suitable mechanism for feeding the box blanks continuously to the machine will meet the requirements of the invention.

The main features of the mechanism consist 100 of a supporting frame —1^a, an inclined table —4, upon which the box blanks are placed in suitable quantities. The blanks

are delivered singly from the table —4, by a pick-up roller —5, coacting with a reciprocating pick-up roller —6, which is operatively connected with a geared cam wheel —7, by crank connections —8 —9 —10; pick-up roller —5 being geared to a ratchet —11 which in turn is connected to a pitman 110

wheel —12 by a rod —13. From the pick-up rollers —5 —6, the blanks are delivered to the opposite end of the feeder by a carrier belt —14, operating over a feed roller 5 —15, geared to cam wheel —7 and an idle roller —16, adjacent the pick-up rollers —5 —6. The blanks are held in frictional contact with belt —14 by a series of vertically disposed guide strips —17, arranged longitudinally of the machine and supported on cross rods —18. Pitman wheel —12 is geared to cam wheel —7 which in turn is operatively connected to the main drive shaft —19 of the machine by a gear train 15 —20, —21, —22, —23, —24, —25, —26, as best shown in Fig. 2.

From the carrier belt —14 the box blanks are brought under control of opposite carrier belts —27, —28, arranged in vertical planes above and below the longitudinal center line of the machine. Belt —27 is driven by a roller —29, and travels idle rollers —32 —33 in its upper course and a roller —34 and the drive roller —29, in the lower course of travel. Belt —28, is driven by a drum —34^a, at the delivering end of the machine and traverses the drum —34^a and an idle roller —35, adjacent the feeding mechanism, in its upper course of travel 30 and idle rollers —36 —37 —38 in its lower course, roller —37 being mounted on a pivoted belt tightener arm —39. At the receiving end of belts —27 and —28, opposite pick-up rollers —40 —41, act on the box blanks to bring the same under control of the belts, the upper roller being geared to cam wheel —7.

As the box blanks pass from the pick-up rollers 40 —41, the opposite front corners —a, (see Fig. 11) of the blanks, as they pass through the machine, are moved into engagement with tension elements —43, spring clips as here shown, which act to turn the side edges of the portions —a, upwardly as the blanks pass over the clips, and as the same are moved into contact with opposite rollers —45 disposed at an angle on opposite sides of the carrier belts —27 —28. As the corner portions —a of the blanks engage rollers —45 the intermediate portion —b of the front of the blanks is engaged by opposite guides —46 which act together with belt —27 to hold the blanks down, thus causing a fold to be made on lines —c at each opposite front corner of the blanks as illustrated in Fig. 12, as the same are forced against and under rollers —45 by the feeding action of the carrier belts.

The detail mechanism of rollers —45 and guides —46 is best shown in Figs. —3 and —4. Each roller is supported rotatably in the lower ends of depending posts —47 which have their upper ends reduced 60 and threaded to receive a nut —48 by which

means the posts are secured in slots —49 of cross bars —50 which are secured to the frame of the machine by means of brackets, the slots —49 providing for adjustment of rollers —45 laterally to adapt the same for different sizes of box blanks. Guides —46 are supported on the lower ends of depending arms —52 secured to a cross bar —53, which is supported on a bar —54, extending longitudinally of the machine and serving as a support for opposite longitudinal members —55, in a lower plane which, together with a second pair of opposite longitudinal members —56, act as guides for the box blanks through the machine. Vertical adjustment of guides —55, to regulate the spacing between guides —55, and 56, to adapt the same to variations in the box blanks, is provided for by means of adjusting bolts —57 and hand screw heads —58, 80 by means of which guides —55 are connected to member —54.

As the box blanks pass from the folding rollers —45, the inner edges of the folded portions —a pass under opposite guides —59 secured to a cross rod —60 which is supported at its opposite ends in one of the cross frame members —3, the guides acting to further compress the folded corners of the blanks and also to maintain the alignment of the blanks as the same are advanced under the second set of opposite guides —46 and over a second set of folding devices —61 which act to fold the opposite rear corners —a' in the same manner as the front corners —a, the folding operation being accomplished without interrupting the forward movement of the blanks through the machine.

The folding devices —61, as here shown, are mounted on the under side of a plate —62, supported on a frame cross bar —63, the folding devices being mounted on the inner ends of shafts —64, supported in brackets —65 secured to plate —62, and operable rotatably through slots —66 in plate —62. The opposite ends of shafts —64 are connected by means of a ratchet mechanism —67, or any suitable connection, to piston racks —68 of opposite air cylinders —69, the racks being supported by guides —68^a, and operated in one direction by springs —68^b. The connection to the cylinders is such that shafts —64, and with the shafts the folding devices —61, are operated by a half turn upon each actuation of the air cylinders. Air is admitted to the cylinders from an air line —70 and branch connections 71 —72 by means of a spring pressure valve —73 in air line —70, the air line and valve being supported on a depending plate, or bracket —74 secured to one of the lower guide members —56, as best shown in detail Fig. 10. Also supported in bracket —74 is a pawl —75, operatively connected 120

with valve —73 and a ratchet connection —76 adapted to actuate pawl —75, the ratchet mechanism including an arm —77 extending upwardly into the path of the 5 box blanks, and adapted to be actuated by engagement thereof by the front edges of the blanks whereby to actuate valve —73, to admit air to cylinders —69, the operation being so timed that the rear corners —a' 10 of the blanks will be in position over devices —61 to be folded by the operation thereof, as best illustrated in detail Fig. 6. Operation of the folding devices —61 is much faster than the movement of the box blanks, 15 thus enabling the folds to be made without retarding the forward movement of the blanks. Upon actuation of arm —77, by a box blank, the blank passes over the free end of the arm, the arm being then retracted 20 to normal position to be engaged by the next blank by a spring —78.

As the box blanks pass from the second folding operation the same are engaged by additional upper belts —79 arranged on opposite sides and outwardly of upper carrier belt —27. Belts —79 traverse rollers —80 —81 and —82, and in their lower course contact with the outer margins of the folded portions —a and —a' of the blanks, thus 30 acting with belts —27 and —28 to move the blanks forward, and acting further independently of belts —27 and —28 to flatten the folds as the blanks are moved into register with the gluing mechanism. Belt 35 pulleys —80 and —81, are supported in the opposite ends of arms —83 secured to brackets —84, which in turn are secured on a shaft —85 having its ends supported in brackets on the side frames of the machine. 40 Arms —83 are adjustable longitudinally on brackets —84 by means of slots —86 which provide for regulating the proximity of belt 79 to the box blanks. Belt tighteners —87 are also provided for belt —79 adjacent 45 pulleys —82.

The gluing mechanism, as here shown, comprises four separate glue containers —88 of the character shown and described in detail in my copending application for patent 50 Serial No. 664,415 filed September 24, 1923. As the detail construction of the gluing devices forms no part of the present invention, only the general arrangement and operation of the mechanism will be herein described. 55

Each of the glue containers is provided in its bottom with a plurality of apertures forming ports for the discharge of the glue, each port being normally closed with a stem 60 —89 which projects through the ports and is adapted to be pressed upwardly, upon being moved into engagement with the box blanks as the containers —88 are reciprocated, thus causing a small portion of glue 65 to escape through each port and to be de-

posited on the blanks, as indicated at —e in Fig. 12 from the ends of stems —89. The stems —89 are adapted to be reversed end for end, their opposite ends acting as plugs for the ports, thus some of the ports can be 70 closed as desired to regulate the deposit of glue to the size and shape of the glue surfaces of the blanks.

The glue containers are secured by means of brackets —90 to rods —91, extending transversely of the machine, and supported in oscillating bearing blocks —92 hung on shafts —94 which in turn are supported in brackets —1^b, extending upwardly from its side frames —1, as best shown in Figs. 3 80 and 5. The bearing blocks —92 are mounted eccentrically as indicated at —93, in Fig. 5, on shafts —94, the shafts being connected one to the other from opposite sides of the machine by a chain —95 and sprockets —96. 85 On the left side of the machine as viewed in Fig. 5 an air cylinder —97 is mounted on the bracket —1^b, and is connected to shaft —94, by a piston rack —98, and a gear —99, the gear having a ratchet connection with 90 the shaft as indicated at —100 to provide for idle operation of rack —98 in one direction. Air for operating the rack is admitted to cylinder —97 from air line —70 through a branch connection —101, which is provided with a valve connection —102, of the same construction as that shown and described in connection with detail Fig. 10, the valve being operated to admit air to cylinder —97 by an arm —77^a, which is engaged by the front edge of the box blanks as the same move into position under the containers —88 to receive a deposit of glue therefrom. Upon each operation of the 95 valve, shafts —94 are operated a full turn 100 and each container —88 is reciprocated vertically, thus bringing port stems —89 into contact with portions d—d, of the blanks and making a deposit of glue thereon. A plate —103 supported on a cross rod —104 105 by means of brackets —105, as best shown in Fig. 5, supports the blanks from beneath as the glue is deposited thereon, thus providing for even contact with the glue surfaces of d—d, to effect a uniform deposit of 110 glue thereon.

As the blanks pass from the gluing mechanism the same are engaged by a second upper carrier belt —27^a, traversing pulleys —27^b, 27^c, 27^d, and sustaining the same relation to the lower carrier belt —28 and the box blanks as upper carrier belt —27, which extends only to the gluing mechanism. The blanks are also engaged at this point by opposite cross belts —106, traversing pulleys —107 and —108, pulleys —107 being mounted in brackets —109, which are slidably secured to a cross bar —110, by means of a slot —111, pulleys —108 being adjustable 125 slidably on their operating shaft —112. 130

Thus the belts —106 are adapted to be spaced variably laterally one from the other to adapt the same to blanks of different sizes. The belts act on the blanks, in a manner well known in this art, to turn the opposite side portions —d upwardly at an angle to effect a complete fold of these portions as the blanks pass between pressure rollers —113 which act to press the folded portions —a —a' and d—d firmly together and thus to form adhesive junctures therebetween. From rollers —113 the blanks are delivered in knocked-down form over a series of carrier belts —114 —115 —116, of well known construction, to the delivery end of the machine, the blanks being stacked against a stop —117 and removed in quantities suitable for handling by the machine attendant.

20 A power belt wheel —19^a is secured to the main drive shaft —19 of the machine, operating movement from the shaft being transmitted to the delivery end of the machine by a belt —118 traversing pulleys —119 and —120, pulley —120 being connected to a drive shaft —121 which is connected to the various belt units by gear trains —112, —123, —124 and —125, —122, —123, —126, —127 and —128, —126, —219 and —130, —126, —129, —131 and —132, as illustrated in Fig. 2.

With respect to the air cylinders —69 and —97 and the air line connections thereto, it will be obvious that electrical devices, as magnets, or motors, and electrical connections, including contact switches in place of valves —73, can be readily substituted for these parts and used with equal advantage in the operation of the machine.

40 From the foregoing detailed description and the drawings the construction and operation of my improved machine will be readily understood. The invention with respect to the air operated folding and gluing mechanisms is broadly new in this art, and has been broadly defined in certain of the appended claims.

Having described my invention, I claim:

50 1. A box making machine including in combination with feeding mechanism for paper box blanks and means for moving the same on said machine, means disposed in the path of the blanks below the plane of movement thereof as the same pass from the feeding mechanism, in position to be engaged by the blanks and adapted to act on the front corners thereof to turn the same upwardly, means arranged farther along in the path of the blanks above their plane of movement, adapted to be engaged by said turned corners, and acting to form a fold thereof, means acting on the blanks to fold the rear corners thereof, means to apply an adhesive thereto, and means to effect further foldings thereof whereby to form adhesive junctures between said folded portions.

55 2. A box making machine including in combination with feeding mechanism for paper box blanks and means for moving the same on said machine, tension elements disposed in the path of the blanks below the plane of movement thereof as the same pass from the feeding mechanism, in position to be engaged by the blanks and adapted to act yieldingly on the front corners thereof to turn the same upwardly, means arranged farther along in the path of the blanks above their plane of movement, adapted to be engaged by said turned corners, and acting to form a fold thereof, means acting on the blanks to fold the rear corners thereof, means to apply an adhesive thereto, and means to effect further foldings thereof whereby to form adhesive junctures between said folded portions.

60 3. A box making machine including in combination with feeding mechanism for paper box blanks and means for moving the same on said machine, opposite spring clips disposed in the path of the blanks as the same pass from the feeding mechanism, in position to be engaged by the blanks and adapted to act yieldingly on the under side of the front corners of the blanks to turn the same upwardly, means arranged farther along in the path of the blanks above their plane of movement, adapted to be engaged by said turned corners, and acting to form a fold thereof, means acting on the blanks to fold the rear corners thereof, means to apply an adhesive thereto, and means to effect further foldings thereof whereby to form adhesive junctures between said folded portions.

65 4. A box making machine including in combination with feeding mechanism for paper box blanks and means for moving the same on said machine, means disposed in the path of the blanks below the plane of movement thereof as the same pass from the feeding mechanism, in position to engage the front corners thereof to turn the same upwardly, opposite pressure devices arranged above the plane of movement of the blanks farther along in their path adapted to engage said turned corners and acting to form a fold thereof, means acting on the blanks to fold the rear corners thereof, means to apply an adhesive thereto, and means to effect further foldings thereof whereby to form adhesive junctures between said folded portions.

70 5. A box making machine including in combination with feeding mechanism for paper box blanks and means for moving the same on said machine, means disposed in the path of the blanks below the plane of movement thereof as the same pass from the feeding mechanism, in position to be

75 adhesive junctures between said folded portions.

75 6. A box making machine including in combination with feeding mechanism for paper box blanks and means for moving the same on said machine, tension elements disposed in the path of the blanks below the plane of movement thereof as the same pass from the feeding mechanism, in position to be engaged by the blanks and adapted to act yieldingly on the front corners thereof to turn the same upwardly, means arranged farther along in the path of the blanks above their plane of movement, adapted to be engaged by said turned corners, and acting to form a fold thereof, means acting on the blanks to fold the rear corners thereof, means to apply an adhesive thereto, and means to effect further foldings thereof whereby to form adhesive junctures between said folded portions.

80 7. A box making machine including in combination with feeding mechanism for paper box blanks and means for moving the same on said machine, opposite spring clips disposed in the path of the blanks as the same pass from the feeding mechanism, in position to be engaged by the blanks and adapted to act yieldingly on the under side of the front corners of the blanks to turn the same upwardly, means arranged farther along in the path of the blanks above their plane of movement, adapted to be engaged by said turned corners, and acting to form a fold thereof, means acting on the blanks to fold the rear corners thereof, means to apply an adhesive thereto, and means to effect further foldings thereof whereby to form adhesive junctures between said folded portions.

85 8. A box making machine including in combination with feeding mechanism for paper box blanks and means for moving the same on said machine, means disposed in the path of the blanks below the plane of movement thereof as the same pass from the feeding mechanism, in position to be engaged by the blanks and adapted to act yieldingly on the front corners thereof to turn the same upwardly, opposite pressure devices arranged above the plane of movement of the blanks farther along in their path adapted to engage said turned corners and acting to form a fold thereof, means acting on the blanks to fold the rear corners thereof, means to apply an adhesive thereto, and means to effect further foldings thereof whereby to form adhesive junctures between said folded portions.

90 9. A box making machine including in combination with feeding mechanism for paper box blanks and means for moving the same on said machine, means disposed in the path of the blanks below the plane of movement thereof as the same pass from the feeding mechanism, in position to be engaged by the blanks and adapted to act yieldingly on the front corners thereof to turn the same upwardly, opposite pressure devices arranged above the plane of movement of the blanks farther along in their path adapted to engage said turned corners and acting to form a fold thereof, means acting on the blanks to fold the rear corners thereof, means to apply an adhesive thereto, and means to effect further foldings thereof whereby to form adhesive junctures between said folded portions.

engaged by the blanks and adapted to act on the front corners thereof to turn the same upwardly, opposite pressure devices arranged above the plane of movement of the blanks at an angle to the direction of movement, farther along in their path, adapted to engage said turned corners and acting to form a fold thereof, means acting on the blanks to fold the rear corners thereof, means to apply an adhesive, and means to effect further foldings thereof whereby to form adhesive junctures between said folded portions.

6. A box making machine including in combination with feeding mechanism for paper box blanks and means for moving the same on said machine, means disposed in the path of the blanks as the same pass from the feeding mechanism, in position to be engaged by the blanks and adapted to act on the front corners thereof to turn the same upwardly, opposite pressure rollers arranged above the plane of movement of the blanks farther along in their path, said rollers being adjustable laterally to suit the size of the blanks, and acting to engage said turned corners to form a fold thereof, means acting on the blanks to fold the rear corners thereof, means to apply an adhesive thereto, and means to effect further foldings thereof whereby to form adhesive junctures between said folded portions.

7. A box making machine including in combination with feeding mechanism for paper box blanks and means for moving the same on said machine, means adapted to fold the front corners of the blanks as the same pass from the feeding mechanism, means comprising opposite rotatable members normally in a plane below the plane of movement of the blanks, adapted to engage the blanks from beneath and fold the rear corners thereof in like manner to the folding of said front corners, means to apply adhesive to the blanks, and means to effect further foldings thereof whereby to form adhesive junctures between said folded portions.

8. A box making machine including in combination with feeding mechanism for paper box blanks and means for moving the same on said machine, means adapted to fold the front corners of the blanks as the same pass from the feeding mechanism, means comprising opposite shafts rotatably supported in a plane below the plane of movement of the blanks and having lateral extensions adapted to engage the blanks from beneath and fold the rear corners thereof, means to apply an adhesive to the blanks, and means to effect further foldings thereof whereby to form adhesive junctures between said folded portions.

9. A box making machine including in combination with feeding mechanism for

paper box blanks and means for moving the same on said machine, means adapted to fold the front corners of the blanks as they pass from the feeding mechanism, means comprising opposite shafts disposed at an angle one to the other in a plane below the plane of movement of the blanks and having opposite lateral extensions adapted alternately to engage the blanks from beneath and effect an upward fold of the rear corners thereof, means to apply an adhesive to the blanks, and means to effect further foldings thereof whereby to form adhesive junctures between said folded portions.

10. A box making machine including in combination with feeding mechanism for paper box blanks and means for moving the same on said machine, means adapted to fold the front corners of the blanks as the same pass from the feeding mechanism, means comprising an air line, means adapted to be actuated by the blanks for controlling the air line, and means operatively connected to the air line adapted to be actuated by air pressure therefrom upon actuation of said controlling means to effect a fold of the rear corners of said blanks, means to apply an adhesive to the blanks, and means to effect further foldings thereof whereby to form adhesive junctures between said folded portions.

11. A box making machine including in combination with feeding mechanism for paper box blanks and means for moving the same on said machine, means adapted to fold the front corners of the blanks as the same pass from the feeding mechanism, means comprising an air line including a valve for controlling the air line, a valve connection extending into the path of the blanks and adapted to be actuated by the blanks, and means operatively connected to the air line and adapted to be actuated by air pressure therefrom upon operation of said valve to effect a fold of the rear corners of said blanks, means to apply an adhesive to the blanks, and means to effect further foldings thereof whereby to form adhesive junctures between said folded portions.

12. A box making machine including in combination with feeding mechanism for paper box blanks and means for moving the same on said machine, means adapted to fold the front corners of the blanks as the same pass from the feeding mechanism, means comprising an air line and connections for controlling the air line adapted to be actuated by said blanks, and means operatively connected to the air line including opposite air cylinders and a member connected to each cylinder and adapted to effect a fold of a rear corner of said blanks upon actuation of said connections, means to apply an adhesive to the blanks, and means to effect further foldings thereof whereby to

- form adhesive junctures between said folded portions.
13. A box making machine including in combination with feeding mechanism for paper box blanks and means for moving the same on said machine, means adapted to fold the front corners of the blanks as the same pass from the feeding mechanism, means comprising a source of power and connections for controlling the same adapted to be actuated by said blanks, means operatively connected to said source and adapted upon actuation of said controlling means to be actuated by power therefrom to effect a fold of the rear corners of said blanks, means to apply adhesive to the blanks, and means to effect further foldings thereof whereby to form adhesive junctures between said folded portions.
14. A box making machine including in combination with feeding mechanism for paper box blanks and means for moving the same on said machine, means comprising a source of power and connections for controlling the same including a part in the path of the blanks as the same move over the machine and adapted to be actuated thereby to release said power, and means operable by power so released to effect a fold of said blanks.
15. A box making machine including in combination with feeding mechanism for box blanks and means for moving the same on said machine, means comprising a source of power independent of said machine and connections for controlling the same including a part adapted to be actuated by each paper blank, in its forward movement on said machine, to release said power and upon the passing of each blank to be actuated by means independent of the blanks to shut-off said power, and means connected to said source and adapted upon operation of said power releasing means to be actuated by power therefrom to effect a fold of a paper blank.
16. A box making machine including in combination with feeding mechanism for box blanks, means to fold the blanks, means comprising a source of power and connections for controlling the same adapted to be actuated by the paper blanks, gluing mechanism connected to said source and adapted to be operated by power therefrom to apply glue to the blanks upon actuation of said controlling connections, and means adapted to further fold the blanks to effect adhesive junctures between folded portions thereof.
17. A box making machine including in combination with feeding mechanism for box blanks, means to fold the blanks, means comprising a source of power and connections for controlling the same including a part in the path of the paper blanks as the same move over the machine adapted to be engaged and actuated by the blanks to release said power and to be actuated to shut-off the power upon being disengaged by the blanks, gluing mechanism connected with said source of power and adapted to be operated with power therefrom transmitted through said connections to apply glue to the blanks, and means adapted to further fold the blanks to effect adhesive junctures between folded portions thereof.
18. A box making machine including in combination with feeding mechanism for box blanks and means for moving the same on said machine, means to fold the blanks, means comprising a source of power and connections for controlling the same adapted to be actuated by the box blanks in their movement over said machine, means connected with said source and said connections and adapted to be operated upon actuation of the latter by power from said source to fold said blanks, other means for controlling said power adapted to be actuated by the paper blanks subsequent to said folding operation, and other means connected with said source of power and the second named controlling means therefor and adapted to be operated upon actuation of the latter with power from said source to apply glue to the blanks, and means adapted to further fold the blanks to effect adhesive junctures between folded portions thereof.
19. The herein described method of making paper boxes consisting in causing suitable box blanks to be delivered through a box making apparatus, in causing the blanks to effect operation of controlling means of a source of power independent of said apparatus, to release said power, and in utilizing the power so released to actuate mechanism to effect foldings of said blanks.
20. The herein described method of making paper boxes consisting in causing suitable box blanks to be delivered through a box making apparatus, in causing the blanks to effect operation of separate units of controlling means of a source of power, independent of said apparatus, to release said power successively, and in utilizing the power so released to actuate mechanism to effect foldings of the blanks and to apply an adhesive substance thereto, and in causing further foldings of the blanks to be made on said apparatus to form adhesive junctures between said folded portions.
- In testimony whereof, I affix my signature.

SAMUEL BERGSTEIN.
